Primary Examiner — David Muller(74) *Attorney, Agent, or Firm* — Sturm & Fix LLP(57) **CLAIM**

The ornamental design for an IV pole tray and bracket, as shown and described.

DESCRIPTION

FIG. 1 is a perspective view of an IV pole tray and bracket showing my new design; wherein the clamp and tray bracket are configured such that the clamp is disposed to engage a vertical pole;

FIG. 2 is a left-side elevational view thereof;

FIG. 3 is a right-side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view of an IV pole tray and bracket showing my new design; wherein the clamp and tray bracket are configured such that the clamp is disposed to engage a horizontal rail;

FIG. 9 is a left side elevational view thereof;

FIG. 10 is a right side elevational view thereof;

FIG. 11 is a front elevational view thereof;

FIG. 12 is a rear elevational view thereof;

FIG. 13 top plan view thereof; and,

FIG. 14 is a bottom plan view thereof.
